DUAL RING ELEMENT CONTAINER CLOSURE

James W. Dimmock, Hazelcrest, Ill., assignor to The Sherwin-Williams Company, Cleveland, Ohio, a corporation of Ohio

Application September 4, 1956, Serial No. 607,644

2 Claims. (Cl. 220—55)

This invention relates to an improvement in container closures, wherein the container is adapted to a use requiring repeated openings and closing as the contents of the container are consumed.

More particularly, this invention relates to dual element container closures comprising an inner container-stoppering disk element about the periphery of which depend a plurality of flexible fingers adapted to engage a peripheral groove of a correlated container mouth and a ring element adapted to circumscribe and compress said fingers into a locked position in and about the peripheral groove below the container mouth. Dual element container closures of the class to which this improvement relates are described generally in U. S. Patent 2,045,480, of July 23, 1936.

In order to best understand the present invention and its improvement over the prior art, I refer first to the drawings, in which:

Figure 1 is a full front view showing a fragmentary container with the dual element closure home over the mouth thereof.

Figure 2 is an exploded sectional view of the elements inherent in Figure 1, detailing container mouth *c*, container-stoppering disk *b*, and ring element *a*.

Figure 3 is an enlarged fragmentary sectional view through line 3'-3' of Figure 1.

Figure 4 is a fragmentary view, partially in section, of the first draw in the manufacture of dual ring element *a* of Figure 2.

Figure 5 is a fragmentary view, partially in section, of the second draw in manufacture of dual ring element *a*.

Figure 6 is a view, partially in section, of the final dual ring after the last operation in its manufacture.

As will be observed generally in the foregoing figures, container having a mouth similar to *c*, and an inner container-stoppering disk element *b* have been previously described in the art and have been extensively used in paint cans, for example, over the past 20 years.

The dual element container closure has been outstandingly useful, but has also suffered two outstanding drawbacks during its extensive application to modern packaging of materials not always completely consumed the first time the container is opened.

The first drawback in the prior art container of the class of interest is that it has been most difficult to adopt the container and dual element closure to purely mechanical capping. U. S. Patent 2,734,673, of February 14, 1956, has described an automatic closure machine which has been used successfully, so long as the exterior bead (corresponding to interior bead 15 in Figure 2-*a*) is relatively broad in horizontal dimension. Unfortunately, when the bead is made heavy enough to assure fool-proof automatic capping (not requiring the presence of an operator) there is a tendency for the broad bead, upon jostling the cans against one another during handling and shipping, to cause adjacent can ring elements to be loosened and removed. Losses in goods packed often results.

A second drawback is that when filled containers are

2

stacked in packed cartons in accordance with present day warehousing practices, the load on the top of the individual container is transferred to the skirted flange 3 lying between the chime 2 of the container and the container mouth 6. At relatively light loading, the skirted flange 3 is permanently deformed. Deformation, in turn, most often lowers only one side of the container and the stacked and cartoned goods slide from stacked pallets. In turn, so damaged cans are lacking in appeal to the ultimate purchaser of the packaged goods.

It is a principal object of this invention to strengthen containers of the class described by a relatively simple change in construction of the ring element of the dual element container closure.

It is a further object of this invention to provide a ring element which will feed through an automatic capping machine without jamming the machine due to minor variations in ring diameter.

These and other objects will be more apparent as the description of the invention is developed.

Referring in general to the drawings, container 1 terminates in its largest diameter at its top in chime 2 which constitutes a plurality of thicknesses of metal and hence is the strongest part of container 1.

From chime 1, a funnel-like skirt member 3 is drawn inwardly and upwardly above the chime to lead into a flat annular stop 4. An inwardly drawn peripheral groove 5 extends upwardly from stop 4 to form container mouth 6 finished by means of an inwardly (or outwardly) rolled bead 7.

The inner disk element *b* of Figure 2 provides a domed disk 8 of slightly larger diameter than that of bead 7 of container mouth 6. The domed disk 8 terminates in a relatively flat annulus 9 adapted to fit over bead 7 and containing on the under side thereof a soft gasketing material 10, to provide a seal between the metal surfaces.

Depending from the outer periphery of disk 8 and annulus 9 are a plurality of yieldable fingers 11, whose tips terminate in rolls 12 which tips are adapted to engage peripheral groove 5 of container 1 passing over mouth section 6 when disk element *b* is closed over container mouth, *c*.

The improvement to which this invention is directed is in the ring element *a* adapted to circumscribe yieldable fingers 11 and to compress rolled tips 12 thereof into locking engagement by means of the joints 13 and 14 in fingers 11 and ring wall 20 respectively. Engagements at these points hold finger tips 12 securely in and about peripheral groove 5 of correlative container mouth section 6 and 7.

The improved dual ring element *a* of this invention may be formed from a flat piece of sheet stock in three operations as illustrated by means of Figures 4, 5 and 6. The first draw produces a ring of U-shaped cross section.

55 The second draw (Figure 5) forms annular beads 16 and 15 at the free ends of the centers of these beads which lie in slightly different planes. In the third draw, base 17 of the U is drawn inwardly at a fixed height above (below) bead 15 to form an annular lip 18, of somewhat less diameter than the outer diameter of flat annulus 9 of domed disk element *b*. The height of wall 20 from the terminus of bead 15 to the under side of lip 18 is designed to be equivalent in dimension to the distance from the top side of the flat annulus 9 to the flat annular stop 4 of top *c* of container and below peripheral groove 5 of *c*. Base 17 of U-shaped dual ring *a* (or top of the dual element ring) is illustrated as being essentially flat, but is preferably made slightly convex in practice, for additional strength is gained thereby.

70 The dual ring *a* of the invention illustrated in enlarged section in Figure 3, demonstrates the correlation of the novel ring with the prior art inner disk *b* and container

1 mouth *c* when the container is closed, as illustrated in Figure 1. In closed position, inner disk element *b* is seated over mouth 6 and bead 7 of container 1 by means of annular sealing gasket material 10 on the under side of annular section 9. Depending fingers 11 are circumscribed and compressed about container mouth 6 and terminal rolls 12 of fingers 11 are locked into contact with container peripheral grooves 5 by means of inner wall 20 of ring *a*. The inner wall 20 of dual ring *a* serves to provide essential compressive and locking action, as previously described. Note that lip 18 of ring *a* transfers downward force to gasket seal 10 to annular bead 17 of the container mouth until contact is made between the first or inner bead 15 and container stop 4. At this point pressure on the gasketing is arrested. As downward forces on the ring *a* exceed the point at which deformation begins in the funnel-like skirt flange 3 of container top *c*, space existing between outer bead 16 and chime 2 of the container 1, left for insertion of an opening tool, is used up until chime 2 and bead 16 are in direct contact. At this time pressure is then transferred directly to the container body wall.

Dual element container closures of the prior art, of commercial quality and gauge metal under test are permanently deformed at a loading of about 650 pounds per square inch. Using the same weight metal commercial container and the dual element closure as herein described, replacing the prior art single ring element with dual ring *a*, about six times the direct top loading can be anticipated without permanent deformation of any part of section *c* of the container. Additionally, automatic closure machinery as described in U. S. 2,734,673 is made more trouble-free in operation by the improvement provided in the dual ring of this invention.

Having described a method for the manufacture of my improved ring, its construction and method of use, what I claim is:

1. In a container and dual closure combination comprising a generally cylindrical container having a mouth interiorly of and conjoined with said container wall forming an upper chime, said mouth extending inwardly and upwardly from said chime to form a tapered throat terminating in an annular bead defining the lip of said container mouth, spaced below said opening an inwardly disposed annular groove defining a horizontal stop in said tapered throat, and said dual closure comprising an inner container-stopping disk element about the periphery of which depend a plurality of flexible fingers, the tips of which are adapted to be distended outwardly over the top portion of said tapered throat to engage said annular groove, and a ring element adapted to circumscribe and compress said fingers into locked position in and about said container groove; the improvement in the ring element which comprises a dual walled ring of inverted generally U-shaped cross-section, the inner vertical annular wall of said ring originating in an annular bead extending vertically upwardly and drawn centrally inwardly at a fixed height to form an annular lip of lesser diameter than said wall, an annular top section extending horizontally outwardly from said lip to a radius substantially equivalent to the radius of the correlated container wall, a second annular wall depending vertically from the outer radius of said ring top section concentric with said first wall, said second wall terminating in a second annular bead, said first and inner bead adapted to rest upon the horizontal terminus of the stop section below the peripheral groove of the container mouth and said second and outer bead adapted to superimposed alignment concentric with and substantially of the same diameter as the chime of said container.

bead extending vertically upwardly and drawn centrally inwardly at a fixed height to form an annular lip of lesser diameter than said wall, an annular top section extending horizontally outwardly from said lip to a radius substantially equivalent to the radius of the correlated container wall, a second annular wall depending vertically from the outer radius of said ring top section concentric with said first wall, said second wall terminating in a second annular bead, said first and inner bead adapted to rest upon the horizontal terminus of the stop section below the peripheral groove of the container mouth and said second and outer bead adapted to superimposed alignment concentric with and substantially of the same diameter as the chime of said container.

5 2. In a container and dual closure combination comprising a generally cylindrical container having a mouth interiorly of and conjoined with said container wall forming an upper chime, said top extending inwardly and upwardly from said chime to form a tapered throat terminating in an annular bead defining the lip of said container mouth, spaced below said opening an inwardly disposed annular groove defining a horizontal stop in said tapered throat, and said dual closure comprising an inner container-stopping disk element about the periphery of which depend a plurality of flexible fingers, the tips of which are adapted to be distended outwardly over the top portion of said tapered throat to engage said annular groove, and a ring element adapted to circumscribe and compress said fingers into locked position in and about said container groove; the improvement in the ring element which comprises a dual walled ring of inverted generally U-shaped cross-section, the inner vertical annular wall of said ring originating in an annular bead extending vertically upwardly and drawn centrally inwardly at a fixed height to form an annular lip of lesser diameter than said wall adapted to rest upon and about the periphery of said inner disk element, an annular top section extending horizontally outwardly from said lip to a radius substantially equivalent to the radius of the correlated container wall, a second annular wall depending vertically from the outer radius of said ring top section concentric with said first wall, said second wall terminating in a second annular bead, said first and inner bead adapted to rest upon the horizontal stop below the peripheral groove of the container mouth and said second and outer bead adapted to superimposed alignment concentric with and substantially of the same diameter as, but spaced apart from, the chime of said container.
